(57) **CLAIM**

The ornamental design for mixing tap, as shown and described.

DESCRIPTION

This application is related to U.S. patent application Ser. Nos. 29/325,865, entitled Mixing Tap; 29/325,866, entitled Mixing Tap; 29/325,869, entitled Mixing Tap; and, 29/325,873, Mixing Tap—all of which were simultaneously filed on Oct. 7, 2008.

FIG. 1 is a front view of a mixing tap showing our new design;

FIG. 2 is a rear view thereof;

FIG. 3 is a perspective view thereof;

FIG. 4 is a left side view thereof;

FIG. 5 is a right side view thereof;

FIG. 6 is a top view thereof; and,

FIG. 7 is a bottom view thereof.

The broken lines showing the interior of the rear of the mixing tap are included for the purpose of illustrating portions of the mixing tap that forms no part of the claimed design.

1 Claim, 1 Drawing Sheet

FIG. 6

FIG. 7
